(57) **CLAIM**

The ornamental design for a snap-in cable clamp, as shown and described.

DESCRIPTION

FIG. 1 is a top perspective view of a snap-in cable clamp showing my new design;

FIG. 2 is a bottom perspective thereof;

FIG. 3 is a top plan view thereof;

FIG. 4 is a front elevational view thereof, the rear elevational view being a mirror image;

FIG. 5 is bottom plan view thereof;

FIG. 6 is a left side elevational view thereof; and,

FIG. 7 is a right side elevational view thereof.

The broken lines in the drawings are for the purpose of illustrating portions of the article that form no part of the claimed design.
